UNITED STATES PATENT OFFICE.

CLARENCE E. MEHLHOPE, OF CHICAGO, ILLINOIS.

GEARING.

1,212,238.

Specification of Letters Patent. Patented Jan. 16, 1917.

Application filed November 18, 1915. Serial No. 62,109.

To all whom it may concern:

Be it known that I, CLARENCE E. MEHLHOPE, a citizen of the United States, and a resident of Chicago, in the county of Cook and State of Illinois, have invented certain new and useful Improvements in Gearing; and I do hereby declare that the following is a full, clear, and exact description thereof, reference being had to the accompanying drawings, and to the letters of reference marked thereon, which form a part of this specification.

This invention relates to improvements in gearing and consists of the matters herein-
15 after described and more particularly point-
ed out in the appended claims.

The gearing is designed particularly for use in connection with a washing machine of the kind known as a pounder washer or
20 vacuum washer, in which a tool, usually in the form of a hollow cone, is fixed to the bottom of an operating shaft or plunger by means of which it is given a vertical, recip-
rocating movement and, in most cases, at
25 the same time an alternating, rotary move-
ment.

The object of the invention is to provide an economical and efficient gearing for the purpose intended by means of which the
30 power, both to vertically reciprocate the operating shaft or plunger and also to alter-
nately rotate said shaft, is applied directly to the shaft (when such movement is de-
sired). The advantages of my invention
35 will appear more clearly as I proceed with my specification.

In the drawings:—Figure 1 is a view representing a side elevation of a washing machine of the kind described provided with
40 my improved gearing for actuating the operating shaft of the washing machine. Fig.
2 is a top plan view of the same. Fig. 3 is a view on an enlarged scale representing a transverse section through the operating
45 end of the lever arm and the operating shaft of the washing machine. Fig. 4 is a perspective view of the same. Fig. 5 is a detail perspective view to be referred to more specifically later in the description.

50 Referring now to that embodiment of my invention illustrated in the drawings:—10 indicates the tub of a washing machine which is supported on legs 11, has a fixed top 12, and a hinged lid 13. The washing machine tub shown is square but manifestly may be of any desired form. The

tub and its hinged lid constitute the supports for the gearing.

As illustrated in the drawings, the lid 13 is hinged to the fixed top 12 of the tub by 60 means of hinges 14, 14.

15 indicates a horizontal shaft which pro-
vides the pintle of the hinges 14, 14, and
which is projected at one side beyond the
tub body. Preferably a reinforced bearing 65
bracket 16 is fixed to the top of the tub near
the side at which the said shaft projects.

17 indicates the operating shaft of the
washing machine and 18 the tool or pounder
fixed at its bottom within the tub body. 70 The tool 18, as has been said, is preferably
conical and hollow and in the present case
opens at its top to the outside air through
the shaft 17 which is made hollow for that
purpose. The specific details of this con- 75
struction are not material to the operation
of the gearing. The shaft 17 depends
through the tub lid and has bearing in a
bracket standard 17^x fixed to and rising
from the top of the lid. 80

19 indicates a lever arm which, as will ap-
pear, is operatively connected to the vertical
shaft 17. The lever, of which the member
19 is an arm, is in this case a bell-crank 85
lever and is placed in substantially a hori-
zontal position, being rigidly connected
with an upright socket arm 20 in which is
fixed a handle 21 in a familiar manner for
grasping and operating the lever.

At the inner operating end of the lever 90
arm 19 is provided a fork 22, which em-
braces the shaft 17. 23, 24 indicate the two
horizontally extending tines of said fork.
One of the tines, namely, the tine 23, has a
slot 23^a in which engages a horizontal pin 95
17^a that extends laterally from the shaft 17.
The other tine 24 is pivotally connected in
any suitable manner to a second horizontally
extending pin 17^b on the shaft 17. The two
pins are preferably placed diametrically op- 100
posite. The connection between the lever
arm 19 and the shaft 17 as described, is such
that when the lever arm has imparted to it a
rocking up and down movement, a positive
up and down movement will be given to the 105
shaft 17. At the same time, by reason of the
horizontal displacement of the pin 17^b in
the rocking movement of the arm 19 from
its uppermost position to its bottommost
position, a rotative swinging movement will 110
be imparted to the shaft 17,—in one direc-
tion when the lever arm 19 is swung

downward and in the opposite direction when the arm 19 is swung upward. The engagement of the pin 17^a with the slot in the fork arm 23 provides for the positive engagement of the lever on both sides of the shaft 17 without interfering with the alternating rotary movement imparted to said shaft in the up and down movement of the lever.

10 High speed balance wheel mechanism may be connected to the lever 21 in any convenient manner. As shown, the shaft 15 has fixed to it beyond the tub, a lever arm 25 and this is connected by a pitman 26^x to a 15 large gear 27 rotatively mounted on the side of the tub and engaged with a pinion 28 on the hub of a fly wheel 29 which is also rotatively mounted on the side of the tub. Thus the rocking movement of the lever arm 19 will be imparted through the shaft 15 to the lever arm 25 and through said lever arm, will impart a continuous rotary movement at high speed to the fly wheel 29 in a familiar manner. Such a mechanism provides for the operation of the machine by a motor, as it will be manifest that by connecting up the wheel 29 to a motor, the lever arm 25 will be driven to swing the lever arm 19 up and down at reduced speed so as 30 to impart the required movement to the operating shaft.

Any suitable means for disconnecting the gearing when opening the lid may be used. As shown, the lever arm 25 is provided with 35 a joint connection with the shaft 15, such that it may be operatively disconnected from said shaft when it is desired to open the lid. The lever arm 25 has a sleeve 25^a at its top which bears upon the end 15^a of the shaft 15 (see Fig. 5, which shows the two parts separated), and a set screw 26 is threaded through the sleeve 25^a and is adapted to engage against a flat part 26^a on the shaft end 15^a. Thus normally the lever arm is rigidly 45 connected with the shaft 15. When, however, the lid is to be opened, the set screw 26 is rotated to withdraw it from engagement with the flat part 26^a on the shaft, whereupon the end 15^a may be rotated within the 50 sleeve 25^a, when it may be opened.

I claim as my invention:—

1. A gearing for washing machines and the like comprising, in combination with a support, an operating shaft depending into 55 said support and capable of vertical reciprocating movement and of an alternating rotary movement, a lever arm, and means directly connecting said lever arm with said operating shaft by which the up and down 60 movement of said lever arm is caused to vertically reciprocate said operating shaft and the horizontal displacement of the means connecting said lever arm with said shaft is used to impart an alternating rotary movement to said shaft.

2. In a gearing, in combination with a support, an operating shaft depending into 70 said support and capable of a vertical reciprocating movement and an alternating rotary movement, a bell-crank lever having an arm connected with said operating shaft, a laterally extending pin on said operating shaft pivotally connected to said operating arm, whereby the up and down movement of said lever arm imparts both a vertical reciprocating movement to said operating shaft and an alternating rotary movement thereto.

3. In a gearing, in combination with a support, an operating shaft depending thereinto and capable of both a vertical reciprocating movement and an alternating rotary movement, a lever arm adapted for actuating said operating shaft, said lever arm having a fork embracing said operating shaft, 85 a pin pivotally connected with one arm of said fork and a second pin engaged in a horizontally extending slot in the other arm of said fork.

4. In a gearing, in combination with a 90 support and an auxiliary support hinged thereto, an operating shaft capable of both a vertical reciprocating movement and alternating rotary movement depending through said hinged support and being capable of vertical reciprocating movement and an alternating rotary movement with reference thereto, a shaft coaxial with the line about which said hinged support is adapted to swing, a lever arm fixed to said shaft, and extending toward said operating shaft, means connecting said lever arm with said operating shaft whereby the up and down movement of said lever arm imparts direct to said shaft both the vertical reciprocating movement and the alternating rotary movement, a fly wheel and high speed 100 gearing connecting the same mounted on said support, means operatively connecting said high speed gearing with said shaft, including a detachable device whereby said hinged support may be swung upon said shaft notwithstanding the normal connection of said shaft with said high speed 110 gearing.

5. In a gearing in combination with a support, an operating shaft or plunger depending into said support and capable of a vertical reciprocating movement, a bell crank lever having an arm connected to said 120 operating shaft or plunger, a fly wheel, gearing for operating said fly wheel at high speed, and means connecting said lever with said high speed gearing.

6. In a gearing in combination with a 125 support, an operating shaft or plunger depending into said support and capable of a vertical reciprocating movement, means providing a vertically alined bearing for said operating shaft, and a lever having an arm 130

adapted for actuating said shaft, said lever arm having a fork embracing said shaft or plunger and operatively connected thereto.

7. In a gearing in combination with a support, an operating shaft or plunger depending into said support and capable of a vertical reciprocating movement, a lever having an arm adapted for actuating said shaft or plunger, said lever arm having a fork embracing said shaft or plunger and operatively connected thereto, a fly wheel,

gearing for operating said fly wheel at high speed, and means connecting said lever with said high speed gearing.

In testimony that I claim the foregoing 15 as my invention I affix my signature in the presence of two witnesses, this 16th day of November, A. D. 1915.

CLARENCE E. MEHLHOPE.
